(57) **CLAIM**

The ornamental design for a display package, as shown and described.

DESCRIPTION

FIG. 1 is a front perspective view of a large display package according to the first embodiment;

FIG. 2 is a rear perspective view thereof;

FIG. 3 is a front view thereof;

FIG. 4 is a rear view thereof;

FIG. 5 is a side view thereof;

FIG. 6 is a side view thereof showing the opposing side;

FIG. 7 is an end view thereof;

FIG. 8 is an end view thereof showing the opposing end;

FIG. 9 is a front perspective view of a small display package according to the second embodiment;

FIG. 10 is a rear perspective view thereof;

FIG. 11 is a front view thereof;

FIG. 12 is a rear view thereof;

FIG. 13 is a side view thereof;

FIG. 14 is a side view thereof showing the opposing side;

FIG. 15 is an end view thereof; and,

FIG. 16 is an end view thereof showing the opposing end.

In the drawings, the broken lines depict unclaimed subject matter only and form no part of the claimed design.

1 Claim, 12 Drawing Sheets
